HENRY W. CLEMENT, OF RUTLAND, VERMONT.

TRANSFER MECHANISM FOR CALCULATING-MACHINES.

1,078,663

Specification of Letters Patent. Patented Nov. 18, 1913.

Application filed January 16, 1913. Serial No. 742,346.

To all whom it may concern:

Be it known that I, HENRY W. CLEMENT, a citizen of the United States, residing at Rutland, county of Rutland, and State of Vermont, have invented a new and Improved Transfer Mechanism for Calculating-Machines, of which the following is a specification.

This invention relates to a novel mechanism for transmitting the tens, hundreds, etc., in calculating machines. This transmission is generally effected by temporarily bringing a transfer finger into engagement with a toothed wheel which is advanced for one tooth during each rotation of said finger.

The present invention comprises novel means for so actuating said finger that it requires for its operation but a minimum expenditure of power and that an accidental displacement of the finger-carrying sleeve from the position to which it has been set, is effectively prevented.

In the accompanying drawings: Figure 1 is a cross section through part of a calculating machine, embodying my invention; Fig. 2 a plan of part of Fig. 1; Fig. 3 a cross section on line 3—3, Fig. 2, and Fig. 4 a similar section through a modified form of the retaining member.

For each digit dial 10, there is provided in the machine frame 11, a squared shaft 12 carrying a toothed sector 18 having a number of teeth 14 that gradually decrease in length. Shaft 12 is rotated through spindle 15 and miter wheels 16, while it in turn transmits its movement to a pinion 17 shown to be slideable on a squared shaft 18. Upon the latter is reciprocably mounted a sleeve 19 carrying a pair of beveled gear wheels 20, either one of which is adapted to engage a similar wheel 21. The latter is keyed to the spindle 22 of the registering dial 10 that displays its numbers through a window 23 of a carriage 24. Intermediate wheels 20 are arranged a shipping bar 26 operated from handle 27 through a lever and link connection 28, whereby the machine may be set either for addition and multiplication or for subtraction and division. Shaft 18 carries

a relatively fixed toothed wheel 29 and a scalloped disk 30 which is adapted to be engaged by the solid section of a mutilated barrel 31 slidably and non-rotatably mounted upon shaft 12, and serving for the purpose of locking dial 23 against accidental rotation. Toothed wheel 29 is adapted to be

engaged by a transfer finger 32 rotatable with barrel 31 and adapted to be axially shifted on shaft 18, so as to be brought into or out of alinement with wheel 29.

For axially displacing barrel 31 and finger 32, spindle 22 is provided with a tappet 33 adapted to transmit its movement by a trigger 34 and a lever 35 to a shipping bar 36. The latter is provided with an arm 37 engaging a circumferential groove 38 formed in the hub or sleeve 39 of barrel 31, said hub also carrying the finger 32 hereinabove referred to. Whenever tappet 33 engages trigger 34, the latter is so tilted by lever 35 as to move shipping bar 36 to the right (Figs. 1 and 2) which movement is transmitted to hub 39 and barrel 31 by arm 37. In this way, finger 32 is brought into alinement with toothed wheel 29, so that upon the rotation of the finger, said wheel will be advanced for one tooth. For subsequently returning the hub and barrel to their original position, the former is provided with a helical cam 40 adapted to engage a fixed abutment 41.

In order to facilitate the reading of the several dials, etc., it is preferred to mount the mechanism described on a slant as illustrated in Fig. 1. The vibrations and severe shocks imparted to the machine during the normal operation thereof will therefore have the tendency to cause barrel 31 after being shifted upward to the right (Fig. 1) to return by gravity to its original position, so that finger 32 will be brought out of alinement with wheel 29 before having actuated the latter. In order to prevent such an objectionable dislodgment of the parts, hub 39 of barrel 31 is provided with a groove 42 extending partly around said hub and having tapering sides 43. This groove is adapted to be engaged by a retaining member shown to be made in the form of a roller 44 having tapering sides. This roller is journaled in a plunge 45 which is reciprocably mounted in a fixed bracket 46, a spring 47 tending to force the roller into groove 42.

The mutual arrangement of the parts is such that when finger 32 has been shifted into its operative position, roller 44 engages groove 42 and thus prevents an accidental axial displacement of hub 39, finger 32 and barrel 31, until the finger had been in operative engagement with toothed wheel 29 and had thus performed its work. Groove 42

gradually merges into the circumference of hub 39 as at 48 after engagement between the parts 32, 29 has taken place, so that roller 44 will be gradually lifted out of the 5 groove and will engage the cylindrical surface of hub 39, so that cam 40 is free to shift the hub together with the parts carried thereby, back to their original position. Whenever tappet 33 causes a movement of 10 hub 39 to the right (Fig. 1) its grooved section is again axially alined with roller 44, so that the spring 47 will assist the trigger in its work and thus reduce the power necessary for the operation of the machine. This 15 is due to the fact that as soon as roller 44 enters groove 42 the spring-influenced engagement of the slanting groove and roller faces will effect a shifting of the hub toward the right.

20 In Fig. 4, roller 44 is dispensed with, and the plunger 45 is provided with a coniform end 49, the bevel of which corresponds substantially to that of the groove sides.

25 It will be seen that by the construction described, all retaining springs hitherto generally employed for holding hub 39 in either of its end positions are dispensed with, so that the work to be performed by tappet 33 is greatly reduced, while the only spring employed assists the tappet in its operation.

30 The subsequent gradual compression of the spring is performed while the tappet is inoperative, so that a great uniformity of movement is obtained and objectionable 35 jerks are avoided.

I claim:

1. In a device of the character described, a rotatable shaft, a hub slidable thereon and carrying a transfer finger, said hub being 40 provided with a cylindrical section and with a circumferential groove that gradually merges into said cylindrical section, a spring-influenced retaining member that normally engages the cylindrical hub section, and means for shifting the hub on the shaft to bring said member into engagement with the hub-groove.
2. In a device of the character described, a spring-influenced retaining member, an 45 inclined rotatable shaft, a hub slidable thereon and carrying a transfer finger, said hub being provided with a cylindrical section and with a circumferential groove that gradually merges into said cylindrical section, means for shifting the hub on the shaft to bring said member into engagement with the hub-groove.

shaft to its lowermost position, the weight of the hub causing the latter to retain such lowermost position whereby the cylindrical hub section is maintained in engagement with the retaining member, and means for 60 raising the hub on the shaft against its weight to bring the grooved hub-section into engagement with the retaining member.

3. In a device of the character described, 65 a spring-influenced retaining member having a chamfered end, an inclined rotatable shaft, a hub slidable thereon and carrying a transfer finger, said hub being provided with a cylindrical section and with a circumferential groove having an inclined side 70 wall and gradually merging into said cylindrical section, means for shifting the hub on the shaft to its lowermost position, the weight of the hub causing the latter to retain such lowermost position whereby the 75 cylindrical hub section is maintained in engagement with the retaining member, and means for raising the hub on the shaft against its weight to bring the grooved hub section into engagement with the retaining member, the engagement between the chamfered end of said member and the inclined groove-wall assisting the raising means in the movement of the hub.

4. In a device of the character described, 80 a spring-influenced retaining member having a chamfered end, an inclined rotatable shaft, a hub slidable thereon and carrying a transfer finger, said hub being provided with a cylindrical section and with a circumferential groove having an inclined side 85 wall and gradually merging into said cylindrical section, a cam surface on the hub, a stationary pin adapted to be engaged by said surface to shift the hub on the shaft 90 to its lowermost position, the weight of the hub causing the latter to retain such lowermost position whereby the cylindrical hub section is maintained in engagement with the retaining member, means for raising the hub 95 on the shaft against its weight to bring the grooved hub section into engagement with the retaining member, the engagement between the chamfered end of said member and the inclined groove-wall assisting the 100 raising means in the movement of the hub.

HENRY W. CLEMENT.
